TAMPERPROOF IDENTIFICATION CARD AND
METHOD OF MAKING THE SAME

Fred S. Carver, Short Hills, N. J.

Application October 24, 1942, Serial No. 463,294

2 Claims. (Cl. 40—2)

The present invention relates to tamper-proof identification cards and methods of making the same.

In order to render identification cards tamper-proof they have been permanently enclosed in plastic by placing the card with the completed identification data on it between two sheets of transparent plastic (usually acetate) and then bonding the paper or card and plastic sheets together under heat and pressure. This renders the card permanent, tamper-proof and readily usable without becoming soiled or torn.

As a further check on the authenticity of an identification card it is quite general to require that the identification card should bear the impression seal of the issuing agency made at the time the card is issued. Attempts to render identification cards with impression seals tamper-proof in the manner above referred to has resulted in the obliteration of the seal when the pressure was applied in the molding operation.

The present invention contemplates improving the process of making the cards so that the proof of the genuine nature of the card, as indicated originally by the seal, can still be retained even though the raised seal itself is obliterated.

The accompanying drawing shows, for purposes of illustrating the present invention, an embodiment in which the invention may take form, it being understood that the drawing is illustrative of the invention rather than limiting the same.

In the drawing:

Figure 1 illustrates an identification card;

Figure 2 is an elevational view of an applicator and block of material;

Figure 3 is an elevational view of the bottom of the applicator;

Figure 4 is an enlarged sectional view showing the use of the applicator;

Figure 5 illustrates the card after the applicator has been used on the seal;

Figure 6 is a section through the card and the plastic sheets and showing the assembly in the press; and

Figure 7 is a sectional view through a finished card.

Figure 1 illustrates an identification card 10 with written or typed in identification material and an impression seal at 11. The card is placed on a flat support S, Figure 4, with the raised side of the seal up. An applicator 12 having a slightly roughened lower surface 13 is rubbed over the surface of a block 14 of carbon, graphite or the like and picks up particles from the block. The rough surface of the applicator may be

readily formed by merely turning the surface flat in a lathe and leaving the tool marks.

The applicator is then placed on the seal bearing area of the card, as indicated in Figure 4,

8 and shifted laterally, usually in a more or less circular motion, so that carbon or graphite particles are transferred onto the raised areas, somewhat as illustrated at 15 in Figure 5. This renders the impression seal very prominent as the particles contrast with the surface of the card.

10 The card is then placed between two sheets of transparent acetate plastic 16—16, Figure 6, to form a sandwich. This sandwich is received between two ferrotyping plates 17—17 and stacks 15 of these sandwiches placed on the platen 18 of a press. The press is then closed, heated and then chilled and the cards with their transparent plastic armor removed and trimmed. The resulting card appears in section at 20 in Figure 7. The impression seal has been completely flattened out, but the particles remaining on the paper are readily visible and the seal is faithfully delineated. The entire card is now tamper-proof and permanent.

20 25 It is obvious that the invention may be embodied in many forms and constructions within the scope of the claims and I wish it to be understood that the particular form shown is but one of the many forms. Various modifications 30 and changes being possible, I do not otherwise limit myself in any way with respect thereto.

What is claimed is:

35 1. The method of rendering an identification card tamper-proof, which comprises applying an impression seal to the card to provide raised areas, then transferring a medium of a color which contrasts with the material of the card so that the raised areas are delineated thereby, placing the card between two sheets of transparent plastic 40 larger than the card, and applying heat and pressure to flatten the "raised" areas and cause the plastic to flow and bond at its edges, the contrasting medium remaining visible to delineate the outline of the seal notwithstanding the flattening of the "raised" seal.

45 2. A tamper-proof identification card comprising a paper sheet carrying identification data and an impression seal having raised indicia 50 forming portions which bear material of contrasting color with the sheet, and an enclosing medium for the sheet comprising a body of transparent plastic permanently united therewith under heat and pressure, the former "raised" portions being flattened out, the contrastingly colored material delineating the impression seal.

FRED S. CARVER.
